(57) **CLAIM**

The ornamental design for a base support for television, as shown and described.

DESCRIPTION

The application file contains at least one drawing executed in color. Copies of this application publication with color drawings will be provided by the Office upon request and payment of the necessary fee.

1. Base support for television
- 1.1 is a front elevation view of a base support for television, showing our new design;
- 1.2 is a back elevation view thereof;
- 1.3 is a left side elevation view thereof;
- 1.4 is a right side elevation view thereof;
- 1.5 is a top plan view thereof;
- 1.6 is a bottom plan view thereof; and
- 1.7 is a perspective view thereof.

The surface color gradient as illustrated in the figures is part of the surface ornamentation integral to the design as claimed.

1 Claim, 7 Drawing Sheets
